UNITED STATES PATENT OFFICE.

HERBERT A. RADFORD, OF DENVER, COLORADO, ASSIGNOR TO U. S. SHUTTER LENS COMPANY, OF DENVER, COLORADO, A CORPORATION OF DELAWARE.

MEANS FOR RELIEVING THE GLARE FROM PROJECTOR LIGHTS.

Application filed March 6, 1926. Serial No. 92,817.

This invention relates to improvements in means for relieving the glare from projector lights and more particularly the headlights of vehicles, which such means are generally known as dimmers or anti-glare devices and the aims of which are well understood in the art.

The primary object of my invention has been to devise substantially improved non-glare means which will at all times maintain maximum road illumination, which may be economically manufactured and marketed, which are simple, durable and effective in operation, and which may be rigidly and 10 facilely installed as an assembled unit to the general types of lamp casings or parabolas, without engaging or marring the reflecting surface of the latter, the improvements as a whole embodying a lens structure that positively 15 carries a shutter-slat element in a directly proximate manner, preferably in facilely attachable and detachable relation therewith, and which device as a combined unit may be appropriately termed as a shutter-lens or a shutter-equipped-lens.

The foregoing and other objects, features and advantages of my improvements, however, will be more clearly apparent as incidental to the following disclosure, and with 20 these general outlining remarks, therefore, reference will now be immediately had to the accompanying drawings, illustrating an embodiment of the invention, in which drawings—

Figure 1 is a front elevational view of a practical adaptation of the improvements as applied to the headlight of an automobile, or 25 an analogous projector lamp; Figure 2 is a substantially vertical sectional view, taken 30 along the vertical central line of Figure 1, the rear portion of the parabola or lamp casing being partially shown in elevation and being partly broken away; and Figure 3 is a central vertical sectional view through a 35 lens proper, with the shutter-slat element omitted.

The numeral 5 indicates a lamp casing, which in the illustration is the reflecting parabola, although in some instances the 40 parabola is separately encased in an outer lamp casing, and it will be obvious that my improvements may be employed with either arrangement. The numeral 6 designates any 45 form of the usual channeled rim disposed

around the open front of the lamp casing, 55 the closure lens being seated therein and suitably held in place in the usual manner, as for instance by a split springy ring 7, and the numeral 8 designates the usual incandescent electric lamp employed. 60

The shutter-slat mask could be supported by any suitable series of lugs projected from the surface of the lens, and in some instances for such lugs might be substituted an integrally continuous flange, the important factor in all instances being that the shutter-slat mask is directly and wholly supported by means projecting from a body face surface of the lens element itself, or as positioned inwardly from the peripheral edge thereof. 70

Describing the arrangement as actually illustrated by the drawings, however, the lens 9 is shown as being provided with a plurality of lugs or shoulders projected from its rear face, a single upper and lower such lug 75 10, and 11, respectively, being only illustrated, but it is obvious that three such lugs could be employed in triangular disposition, or for that matter two upper and two lower lugs could be employed, dependent upon the actual shape of the supporting frame of the shutter-slat element. In actual practice, therefore, it may be more desirable to employ a greater number of such lugs than the pair 80 actually shown, to provide for more effective 85 rigidity against displacement and rattling, and I may prefer the employment of three of such lugs in triangular disposition, to provide for the more facile attachment and detachment of the shutter-slat element, while 90 at the same time preserving said rigidity. It will accordingly be understood that, although in the following description I shall only refer to the paired upper and lower 95 supporting lugs, which embodied my original conception, I do not wish to unnecessarily limit myself in this connection.

These lugs may preferably be made of glass and formed or molded integrally with the lens body, although they could be of other substance and could be otherwise fixedly applied to the lens body, and it is possible that they might be projected from the forward face of the lens body, for applying the shutter-slat element to the front 100 face of the lens body, but these latter arrangements would hardly be so practicable or desirable, and are only mentioned as re- 105

mote expedients. Also, the drawings show a concave lens body, but obviously it might be of other curvature and it might be a flat or planetary lens, and when a concave lens the rim portion may be flattened out as actually shown, for a better fit within the channeled rim 6, or it may be beveled off on its inside face as is quite customary.

The top face of the upper lug 10 may provide for a suspending seat for the encompassing rim 12, or analogous open frame support, of the shutter-slat masking element, hereinafter described, and the bottom face of the lower lug 11 may provide for a base bearing seat for the same. To this end the top face of the upper lug 10 may have a seating recess 13, formed by a forward vertically disposed shoulder 14 and a rearward vertically disposed shoulder 15, the inner face of which latter may be slightly beveled if desired, for a wedging action on said member 12, and the forward bottom face of the lower lug 11 may be provided with a pocket or snap-in socket 16 for the entry of a latching projection on the free end of a clasp spring 17 extending forwardly from the bottom portion of the shutter-slat member 12. It would be considered an equivalent, however, if the male and female elements of this snap-in latching means were reversed.

The shutter-slat masking element may be of any appropriate form, and I make no claim to the same of itself but only broadly as combined with my lens support therefor. This shutter-slat element, however, may embody the open frame support 12 of any suitable shape, for instance in the form of a flat or band ring, within which is disposed a horizontal series of light reflecting vanes, slats or louvers 18 that are so spaced apart vertically with a forward declination or downward slope, whether the slats are plane or arcuate, as to deflect the rays of light forwardly and downwardly in undimmed and concentrated association with the roadway ahead, for conserving maximum illumination, while at the same time obscuring the lamp 8, and reflecting surface therefor, from a position substantially in advance of the same, and thereby eliminating all blinding glare therefrom within the zone extending between the lamp and such advanced position, as will be fully understood.

From Figure 2 it will be obvious that in assembling the lens and shutter-slat element, as they are actually illustrated in the drawings, and which will be marketed in such combined relation for application to existing types and sizes of lamp casings, although the units may be separately supplied for replacement purposes, the central upper portion of the rim 12 is inserted over and suspended from the upper lug 10, as snugly seated within the recess 13, and with the central lower

portion of the rim swung forwardly underneath the lower lug 11, whereupon the forward projection of the clasp spring 17 will engage within the socket 16, thus providing for a snap-in latching means to hold the rim-supported slats firmly in position. With a triangularly disposed arrangement of the supporting lugs, it is doubtful that any latching means would be required, and the apex lug of the triangle could be disposed upwardly, downwardly or otherwise.

While I have thus fully described my invention, it will nevertheless be understood that I do not wish to unnecessarily restrict myself to all of the details exactly as disclosed, excepting as they may come within the terms of the claims, or their equivalent, or as fairly interpreted in the light of the specification if necessary.

What I do claim, as new and patentable, is:—

1. In means for relieving the glare from projector lights, the combination of a closure lens therefor that is provided with supporting means projecting from a face thereof, as positioned inwardly of the peripheral edge of said lens and disposed in a direction around the axis thereof, and a non-glare masking device directly and wholly supported by said projecting means in proximate association with the aforesaid face of said lens, which masking device embodies a vertically spaced series of laterally extending reflecting vanes.

2. In means for relieving the glare from projector lights, the combination of a closure lens therefor that is provided with a plurality of appropriately spaced lugs extending from the rear face thereof, and a non-glare masking device directly supported by said lugs in proximate association with the aforesaid rear face of said lens, which masking device embodies an open frame support for engagement with said lugs and containing a vertical series of appropriately spaced and forwardly declining laterally disposed reflecting vanes.

3. In means for relieving the glare from projector lights, the combination of a closure lens therefor that is provided with a plurality of lugs extending from the rear face thereof, one of said lugs being formed with a seating recess and another with a snap-in socket, and a non-glare masking device directly supported by said lugs in proximate association with the aforesaid rear face of said lens, which masking device embodies an open frame support containing a vertical series of appropriately spaced and forwardly declining laterally disposed reflecting vanes, and one portion of said open frame support being adapted for seating within said seating recess, while another portion thereof is provided with a snap-in spring element for projection within said snap-in socket.

4. As an element of means for relieving the glare from projector lights, of the character disclosed, a closure lens therefor embodying a plurality of lugs formed integrally with and projected from a face of said lens, the said lugs being disposed in spaced relation in a direction around the axis of said

lens, as positioned inwardly of the peripheral edge of the lens, and being adapted to directly and wholly support a non-glare ¹⁰ shutter-slat masking device in proximate association with the aforesaid face of the lens.

In testimony whereof, I affix my signature.

HERBERT A. RADFORD.
